HAIR CURLING DEVICE

William H. Cooper, Columbus, Ohio

Application January 4, 1933, Serial No. 650,190

30 Claims. (Cl. 132—33)

This invention relates to hair curling devices of the type used in connection with machines for imparting a permanent wave to hair and more particularly relates to a winder by means of which a lock of hair is to be curled about a mandrel.

One object of the invention is to provide a winder adapted to be fitted upon a mandrel and as it is turned about the mandrel serves to coil a lock of hair about the mandrel and cause the lock of hair to be smooth and assume a ribbon-like formation as it is wound about the mandrel. By this arrangement, the lock of hair will be closely packed and a good curl formed.

Another object of the invention is to provide the winder with a skirt at one end through which the lock of hair passes and so form this skirt that the lock of hair may be very easily moved into position for extending longitudinally through the skirt and also provide the skirt with a longitudinally extending slot so cut that as the winder is turned, an edge of the slot will serve very effectively to smooth the lock and cause it to assume a ribbon-like formation.

Another object of the invention is to provide the winder with an improved retainer movable into and out of position to extend across the slot of the skirt and not only prevent the lock of hair from slipping outwardly through the slot but also retain the lock in such a position that it will be properly wound about the mandrel in a compact mass during a curling operation.

Another object of the invention is to permit the retainer to be easily moved into or out of a position in which it extends across the slot and also limit movement of the retainer and prevent it from sliding longitudinally off of the winder.

A still further object of the invention is to provide an improved turning key for use in connection with a winder and in this embodiment of the invention, permit the key to be easily engaged with or disengaged from the winder and cause the winder to turn about the mandrel with the key.

Still another object of the invention is to provide a turning key including a winder receiving socket and an actuating shank which engages about a portion of the winder, the socket being formed with a slot to register with the slot of the winder and carrying a collar movable into and out of position to prevent a lock of hair from moving outwardly through the registering slots of the key and winder.

Another object of the invention is to so form the key and winder that after a lock of hair has been wound about a mandrel, the key may be

withdrawn and the winder left in place upon the mandrel and serve to retain the lock of hair tightly wound about the mandrel. By this arrangement, a single key may be used to actuate any number of winders and transferred from one to another as each lock of hair is coiled about a mandrel.

With these and numerous other objects in view, my invention consists in the novel features of construction, combination and arrangement of parts as will be hereinafter referred to and more particularly pointed out in the specification and claims.

In the accompanying drawings forming a part of this application:

Figure 1 is a side elevation showing a winder of the improved construction applied to a mandrel and having its collar or hair retainer moved out of position to close the slot in the skirt of the winder;

Figure 2 is a side elevation showing the winder of Figure 1 with the retaining collar moved into position in which it extends across the slot and a lock of hair partially wound about the mandrel;

Figure 3 is a view showing the winder and a portion of the mandrel partially in elevation and partially in longitudinal section;

Figure 4 is a view taken at right angles to Figure 3 along the line 4—4 of Figure 3 with portions of the winder and mandrel in elevation;

Figure 5 is a transverse sectional view taken through the winder along the line 5—5 of Figure 3 with the mandrel omitted;

Figure 6 is a longitudinal sectional view through the skirt and stem of the winder along the line 6—6 of Figure 5;

Figure 7 is a perspective view of the collar carried by the skirt of the winder and movable into and out of position to close the slot therein;

Figure 8 is a perspective view of the winder with the collar removed;

Figure 9 is a perspective view of the winder looking from the right in Figure 8;

Figure 10 is a view similar to Figure 1 showing a modified form of winder applied to a mandrel;

Figure 11 is a view similar to Figure 10 showing the collar or retainer moved into position to shield the slot, this view being taken at right angles to Figure 10;

Figure 12 is a view showing the modified form of winder in longitudinal section with the mandrel in elevation;

Figure 13 is a view taken at right angles to Figure 12 along the line 13—13 of Figure 12;

Figure 14 is a perspective view of the collar;

5 Figure 15 is a perspective view of the collar looking from the right in Figure 14;

Figure 16 is a sectional view through the collar taken along the line 16—16 of Figure 15;

Figure 17 is a side elevation of the winder with the collar removed;

10 Figure 18 is a side elevation of the winder looking from the right in Figure 17;

Figure 19 is a side elevation of an embodiment of the invention in which a turning key is employed to rotate the winder about the mandrel, 15 the key being shown out of engagement with the winder;

Figure 20 is a side elevation showing the winder engaged within the key and a collar carried by the key moved out of shielding relation to a slot 20 formed in the socket of the key;

Figure 21 is a view similar to Figure 20 showing the collar moved into position to extend across the slot of the socket and a lock of hair partially coiled about the mandrel;

25 Figure 22 is a view showing the key in longitudinal section and the winder and a portion of the mandrel in elevation;

Figure 23 is a side elevation of the winder;

30 Figure 24 is a view of the winder looking from the right in Figure 23;

Figure 25 is another side elevation of the winder looking from the right in Figure 24;

Figure 26 is a view showing the winder in end elevation;

35 Figure 27 is a sectional view through the skirt of the winder, taken along the line 27—27 of Figure 23;

Figure 28 is a view looking at the inner end of the key with the winder in place;

40 Figure 29 is a perspective view of the key with the collar for closing the slot of the socket removed; and

Figure 30 is a perspective view of the collar.

In describing the invention, I shall refer to the 45 drawings in which similar reference characters designate corresponding parts throughout the several views. The improved winder illustrated in Figures 1 through 9 inclusive, consists of a tubular body or stem 1 having a skirt 2 at its 50 inner end and a collar or hair retainer 3 which fits about the skirt and is rotatable thereon in order that it may be moved into and out of position to extend across a slot 4 formed in the skirt and extending longitudinally thereof. The slot has 55 its ends opening through ends of the skirt and by referring to Figures 8 and 9, it will be seen that side edges of the slot extend parallel to each other for a portion of its length and the inner portion of the slot is formed with a side extension 5 which 60 extends circumferentially of the skirt for a portion of its circumference and has a straight cut diagonally extending lower edge 6. The collar 3 when in place rests against the shoulder or out-standing annular flange 7 of the skirt and at its 65 other end is formed with an inwardly extending flange 8 which bears against the shoulder 9 projecting outwardly from the stem or body. A slot 10 to register with the slot 4 is formed through the collar and portions of the inwardly extending 70 flange 8 have been cut away as shown at 11 and 12 and thereby permit a lock of hair to extend longitudinally through the skirt at one side of the body 1 when the winder is in use.

A pin 13 carried by the skirt and screwed into 75 a threaded opening 14 formed therein projects

outwardly through a slot 15 formed circumferentially in the collar and serves to retain the collar in its proper position about the skirt and also serves to prevent the collar from turning about the skirt more than a sufficient distance to move the slot 10 into and out of registry with the slot 4. In other words, the collar may be turned from the position shown in Figure 1 to that shown in Figure 2 after a lock of hair has been engaged through the skirt but it cannot be turned completely about the skirt. It will also be noted that when the collar is moved into position to close the slot 4, as shown in Figure 2, a portion of the collar will extend upwardly from the low end of the inclined edge 6 and serve to retain the lock of hair at an upward incline. By this arrangement, the lock of hair will be fed diagonally of the winder into the skirt and as the winder is turned about the mandrel, the diagonally extending edge 6 will flatten the lock of hair and cause it to assume a ribbon-like formation in which it may be tightly wound as a flat ribbon of hair about the mandrel and a tight coil formed.

Attention is also called to the fact that since 100 the portion 5 of the slot extends upwardly through the shoulder 9 at the inner end of the skirt 2, the lock of hair may slide easily through the skirt while at the same time the inner end 16 of the stem or body 1 will serve to closely pack convolutions of the coil and form a very tight coil of hair about the mandrel. Side arms or wings 17 are provided upon the stem or body to permit easy rotation of the winder and the outer end portion of the body is slit longitudinally as shown at 18 110 in order to permit the body to frictionally grip the mandrel and resist movement of the winder upon the mandrel. Therefore, after a lock of hair has been wound about a mandrel, the winder will remain in a set position and serve as a retainer to prevent the coil of hair from slipping and unwinding.

When this improved winder is in use, the lock 19 at one end of a mandrel 20 is firmly engaged with a lock of hair 21. The winder is fitted 120 upon the mandrel and slid longitudinally thereon to a position in close proximity to the lock 19 and since the skirt has the cuter end of its bore enlarged as shown at 22 and the lock of hair may be easily engaged between the skirt and the mandrel and extended longitudinally of the winder for engagement through the slot 4. A partial turn may be imparted to the winder in order to move the lock of hair into its proper position through the skirt and the collar then grasped 130 and turned to the closed position shown in Figure 2 or merely grasped and further rotation imparted to the winder which will of itself cause the collar to move to a closed position. Rotation of the winder is continued and as it is turned 135 about the mandrel, the lock of hair will be tightly wound about the mandrel and packed tightly thereon by pressure of the inner end 16 of the stem or body. During this winding operation, the free end portion of the lock of hair extends 140 directly away from the diagonally extending edge 6 of the side extension 5 of the slot 4 and this edge will serve to smooth the lock into a flat ribbon which will be guided diagonally into the skirt and prevented from moving out of its proper 145 position by being overlapped by a portion of the collar.

Referring to Figure 5, it will be seen that since the outer face of the skirt is formed with a flat face 23, slot 4 and the side edge 24 of the slot 150

10 extends flush with the surface when the collar is in an open position a lock of hair will very easily move initially into the collar through the registering slots.

5 The winder illustrated in Figures 10 through 18 is somewhat similar to that illustrated in Figures 1 through 9, but its features of construction are different. The tubular body or stem 25 is similar to the stem 1 and has its outer end 10 portion formed with a slit 26 so that when the stem is grasped by its side arms or wings 27 and turned about the mandrel 28, frictional engagement between the mandrel and stem will cause the winder to be retained in a set position upon 15 the mandrel. The skirt 29 corresponding to the skirt 2 projects from the inner end of the stem with the inner end of the stem exposed through the center of the skirt to serve as a packing shoulder for hair coiled about the mandrel and this skirt is formed with a longitudinally extending slot 30 corresponding to the slot 4 and having a side extension 31 corresponding to the side extension 5 and formed with a diagonally extending straight cut lower edge 32. A flat bevelled surface 33 extends along the skirt at one side of the slot 30 in order to permit a lock of hair to readily enter the slot and the adjoining end of the flange 34 extending circumferentially of the skirt is also bevelled to extend flush with the 30 surface 33 as clearly shown in Figure 17. The collar or shield 35 is retained about the skirt with one end resting upon the flange 34 and an inwardly extending flange 36 at its other end bearing against the shoulder 37 of the skirt by 35 a pin 38 carried by the skirt and projecting outwardly through a slot 39 formed circumferentially of the collar. This is similar to the manner in which the collar or shield 3 is retained in place and rotation thereof about the skirt limited. A major feature distinguishing this form 40 of winder from that previously described is the fact that the slot 40 formed longitudinally of the collar is of greater width than the slot 10 and from one side of this slot extends a bill or 45 finger 41 which is curved longitudinally to conform to the circumferential contour of the skirt and is of sufficient length to extend across the slot 30 below the inclined edge 32 of the side extension 31 when the collar is moved to a closed position. By this arrangement, a larger 50 lock of hair may be accommodated as an entrance passage of greater dimension is formed through the collar and skirt when the collar is closed as shown in Figure 11 but at the same time, the finger or bill 41 will serve to engage beneath the lock of hair as it moves inwardly into the skirt during a winding operation and the diagonally extending straight cut edge 32 will serve to flatten the lock of hair and form 55 a ribbon which will be wound tightly about the mandrel and tightly packed thereon.

The winder employed in connection with the form of curler illustrated in Figures 19 through 30, inclusive, is somewhat smaller than those previously described and consists of a stem or tubular body 42 having a skirt 43 extending from its inner end. The stem is slit from its outer end as shown at 44 to permit the stem to have gripping engagement with a mandrel 45 and the skirt is formed with a slot 46 corresponding to the slots 4 and 30 and having a side extension 47 corresponding to the side extensions 5 and 31.

The side extension 47 has a straight cut diagonally extending lower edge serving to smooth 60 a lock of hair and the inner end of the stem

serves to pack the lock of hair in a compact mass as it is wrapped about the mandrel. The stem 42 and the skirt both have their outer surfaces shaped to provide a plurality of flat faces in order that the stem may be grasped and a 65 turn or two imparted to the winder if found necessary.

This winder is to be engaged within a key during a winding operation and it is to be understood that when sold a single key will be 70 supplied with any desired number of winders and transferred from one winder and mandrel to another during use. The winders remain upon the mandrel after a lock of hair has been coiled about each mandrel and, therefore, the 75 winders serve not only as means for coiling a lock of hair about a mandrel but also serve as means for retaining the hair tightly wrapped about the mandrel.

Referring to Figure 29, it will be seen that each 80 key consists of a shank 48 having turning arms or wings 49 and at one end carrying a socket 50 of sufficient size to receive the skirt of the winder as shown in Figure 22. Referring to this figure, it will also be seen that the bore of the shank 85 has its inner end portion enlarged to receive the stem of the winder. By this arrangement, the winder may be entirely enclosed within the socket and inner end portion of the shank and after a lock of hair has been coiled about the mandrel, 90 the key may be slid longitudinally off of the mandrel and leave the winder in place upon the mandrel. A slot 51 to register with the slot 46 is formed longitudinally through walls of the 95 socket and at its upper end communicates with a side extension 52 extending circumferentially of the socket in the head 53 thereof. Along opposite side edges of the slot 51 the walls of the socket have been formed with inwardly bending flanges or lips 54 and 55 which overlap the side 105 edges of the skirt at opposite sides of its slot 46 and cause the winder to be turned about a mandrel with the key.

Referring to Figure 28, it will be seen that the 110 lip 55 is shaped to provide a flat face 56 of such 115 dimensions that it will serve to guide a lock of hair inwardly through the slot 46 into its proper position to extend longitudinally through the winder. It should also be noted that the lock of hair is to be retained at an incline at one side 120 of the registering slots 46 and 51 as it moves through the winder during curling operation as shown in Figure 21 and in order to do so, there has been provided a collar 57 which takes the 125 place of the collars 3 and 35. This collar instead 130 of being applied to the winder is disposed about the socket of the key and is retained in place by a pin 58 carried by the socket and extending outwardly through a slot 59 formed circumferentially of the walls of the collar. Therefore, 135 the collar will be held in place about the socket and its rotation about the socket limited. A slot 60 to register with the slot 51 of the socket is formed through walls of the collar and at its upper end has side extensions 61 and 62 extending circumferentially of the collar through the head 63 thereof and intended to permit free passage of a lock of hair through the head of the 140 collar during a winding operation.

In this embodiment of the invention, the operation is similar to that previously described except that the key and winder are applied to the mandrel and the collar moved to a closed position after the lock of hair is in its proper position, the key and winder being then turned about the 145 150

mandrel as a unit until the hair has been completely wound thereon and the key withdrawn to leave the winder in place upon the mandrel to serve as a securing means for the coil of hair. 5 It will thus be seen that the key serves not only as means for turning the winder but also as means for sliding the lock of hair through the winder and retaining it in its proper angular position as it moves through the winder during a 10 winding operation.

Having thus described the invention, what is claimed is:

1. In a hair curler, a winder adapted to be rotated upon and moved longitudinally of a mandrel, means for securing hair in operative engagement with the winder during a winding operation rotatable about the winder, and a pin carried by said winder and engaging the hair securing means to retain the same in place and 20 limit rotation thereof.

2. In a hair curler, a winder adapted to be rotated upon and moved longitudinally of a mandrel, and rotatably mounted means on said winder movable into and out of position to retain 25 hair in operative engagement with the winder.

3. In a hair curler, a winder adapted to be rotated upon and moved longitudinally of a mandrel, rotatably mounted means in association with said winder movable circumferentially of 30 the winder into and out of position to retain a lock of hair in operative engagement with the winder, and means to retain the last mentioned means in place and limit rotation thereof.

4. In a hair curler, a winder adapted to be rotated upon and moved longitudinally of a mandrel, and means for securing hair in operative engagement with the winder rotatably mounted on and having limited movement circumferentially of the winder.

40 5. In a hair curler, a winder adapted to be rotated upon and moved longitudinally of a mandrel, said winder being formed with a longitudinally extending slot open at its ends whereby a lock of hair may be introduced into the winder 45 for passage through the same during winding and means movable into and out of position to extend across said slot and retain hair in position to pass through the winder.

50 6. In a hair curler, a winder adapted to be rotated upon and moved longitudinally of a mandrel, said winder being formed with a longitudinally extending slot open at its ends whereby a lock of hair may be introduced into the winder 55 for passage through the same during winding, and rotatably mounted means movable into and out of position to extend across the slot and retain hair in operative engagement with the winder.

60 7. In a hair curler, a winder adapted to be rotated upon and moved longitudinally of a mandrel, said winder being formed with a longitudinally extending slot open at its ends whereby a lock of hair may be introduced into the winder for passage through the same during winding, 65 and means for retaining a lock of hair in operative engagement with said winder rotatably mounted and having limited movement circumferentially of the winder.

70 8. In a hair curler, a winder adapted to be rotated upon and moved longitudinally of a mandrel, said winder being formed with a longitudinally extending slot open at its ends whereby a lock of hair may be introduced into the winder for passage through the same during winding, 75 and means for retaining a lock of hair in opera-

tive engagement with said winder rotatably carried by said winder and movable circumferentially thereof into and out of position to extend across the slot.

9. In a hair curler, a winder adapted to be rotated upon and moved longitudinally of a mandrel, said winder being formed with a longitudinally extending slot open at its ends whereby a lock of hair may be introduced into the winder for passage through the same during winding, and means for retaining a lock of hair in operative engagement with said winder rotatably carried by said winder for movement circumferentially thereof and formed with a slot movable into and out of position to register with the slot of the winder when the hair retainer is turned. 80 85 90

10. In a hair curler, a winder adapted to be rotated upon and moved longitudinally of a mandrel, said winder being formed with a longitudinally extending slot open at its ends whereby a lock of hair may be introduced into the winder for passage through the same during winding, a hair retaining collar rotatable circumferentially of said winder and formed with a slot to register with the slot of the winder when the collar is 100 turned in one direction. 95

11. In a hair curler, a winder adapted to be rotated upon and moved longitudinally of a mandrel, said winder being formed with a longitudinally extending slot open at its ends whereby a lock of hair may be introduced into the winder for passage through the same during winding, a hair retaining collar rotatable circumferentially of said winder and formed with a slot to register with the slot of the winder when the collar is 105 turned in one direction and a pin engaged in a track extending circumferentially of said collar to limit rotation of the collar. 110

12. In a hair curler, a winder adapted to be rotated upon and moved longitudinally of a mandrel, said winder being formed with a longitudinally extending slot open at its ends whereby a lock of hair may be introduced into the winder for passage through the same during winding, a hair retaining collar fitting about said winder 120 and formed with a slot to register with the slot in the winder, said collar being rotatable about the winder and formed with a circumferentially extending slot and a pin carried by said winder and extending into the circumferentially extending slot to limit rotation of the collar and prevent movement of the collar longitudinally of the winder. 125

13. In a hair curler, a winder adapted to be rotated upon and moved longitudinally of a mandrel, said winder being formed with a longitudinally extending slot open at its ends whereby a lock of hair may be introduced into the winder for passage through the same during winding, a hair retaining collar fitting about said winder 135 and formed with a slot to register with the slot in the winder, said collar being rotatable about the winder and the collar and winder being formed with circumferentially extending shoulders abutting to prevent sliding of the collar longitudinally of the winder in one direction when in place, a circumferentially extending slot being formed in said collar, and a pin carried by said winder and engaged in the circumferentially extending slot to limit turning of the collar upon 140 the winder and prevent longitudinal movement of the collar off of the winder. 140

14. In a hair curler, a winder adapted to be rotated upon and moved longitudinally upon a mandrel, said winder comprising a tubular body 150

26. In a hair curler, a winder adapted to be rotated upon and moved longitudinally of a mandrel and having a tubular body and a skirt at one end of the body formed with a longitudinally extending slot whereby a lock of hair may be engaged through the skirt and coiled about a mandrel when the winder is rotated, and a key for turning said winder having a tubular shank to rotatably fit about a mandrel and receive the body of said winder, a socket being provided at one end of said shank to receive the skirt of the winder and formed with a longitudinally extending slot to register with the slot of the skirt and means associated with said key to extend across the slot thereof and prevent movement of a lock of hair out of the same.

27. In a hair curler, a winder adapted to be rotated upon and moved longitudinally of a mandrel and having a tubular body and a skirt at one end of the body formed with a longitudinally extending slot whereby a lock of hair may be engaged through the skirt and coiled about a mandrel when the winder is rotated, and a key for turning said winder having a tubular shank to rotatably fit about a mandrel and receive the body of said winder, a socket being provided at one end of said shank to receive the skirt of the winder and formed with a longitudinally extending slot to register with the slot of the skirt and a collar fitting about said socket and formed with a slot moved into and out of registry with the slot of the skirt by rotating the collar.

28. In a hair curler, a winder adapted to be rotated upon and moved longitudinally of a mandrel and having a tubular body and a skirt at one end of the body formed with a longitudinally extending slot whereby a lock of hair may be engaged through the skirt and coiled about a mandrel when the winder is rotated, and a key for turning said winder having a tubular shank to rotatably fit about a mandrel and receive the body of said winder, a socket being provided at one end of said shank to receive the skirt of the winder and having an annular wall and a head connecting the same with the shank, said annular wall being formed with a longitudinally extending slot to register with the slot of the skirt and the head being formed with a circumferentially extending slot extending from the slot in the wall, lips extending inwardly from walls of the socket at opposite sides of the slot formed therein to engage the wall of the winder along opposite side edges of the slot formed therein to cause the winder to turn with the key, and a collar rotatably carried by said socket and formed with a slot moved into and out of registry with the slot of the socket when the collar is turned.

29. In a hair curler, a winder adapted to be rotated upon and moved longitudinally of a mandrel and having a tubular body and a skirt at one end of the body formed with a longitudinally extending slot whereby a lock of hair may be engaged through the skirt and coiled about a mandrel when the winder is rotated, and a key for turning said winder having a tubular shank to rotatably fit about a mandrel and receive the body of said winder, a socket being provided at one end of said shank to receive the skirt of the winder and having an annular wall and a head connecting the same with the shank, said annular wall being formed with a longitudinally extending slot to register with the slot of the skirt and the head being formed with a circumferentially extending slot extending from the slot in the wall, lips extending inwardly from walls of the socket at opposite sides of the slot formed therein to engage the wall of the winder along opposite side edges of the slot formed therein to cause the winder to turn with the key, and a shield carried by said socket and movable into and out of position to extend across the slot of the socket.

30. In a hair curler, a winder adapted to be rotated upon and moved longitudinally of a mandrel and having a tubular body and a skirt at one end of the body formed with a longitudinally extending slot whereby a lock of hair may be engaged through the skirt and coiled about a mandrel when the winder is rotated, and a key for turning said winder having a tubular shank to rotatably fit about a mandrel and receive the body of said winder, a socket being provided at one end of said shank to receive the skirt of the winder and having an annular wall and a head connecting the same with the shank, said annular wall being formed with a longitudinally extending slot to register with the slot of the skirt and the head being formed with a circumferentially extending slot extending from the slot in the wall, lips extending inwardly from walls of the socket at opposite sides of the slot formed therein to engage the wall of the winder along opposite side edges of the slot formed therein to cause the winder to turn with the key and a shield carried by said socket and movable into and out of position to extend across the slot of the socket.
